UNITED STATES PATENT OFFICE.

CHARLES H. BIGBIE AND FRANK G. TANNER, OF LONE GROVE, OKLAHOMA.

REMOVABLE WAGON-COVER.

1,080,948.

Specification of Letters Patent.

Patented Dec. 9, 1913.

Application filed May 20, 1912. Serial No. 698,498.

To all whom it may concern:

Be it known that we, CHARLES H. BIGBIE and FRANK G. TANNER, citizens of the United States, residing at Lone Grove, in the county of Carter, State of Oklahoma, have invented certain new and useful Improvements in Removable Wagon-Covers; and we do hereby declare the following to be a full, clear, and exact description of the invention, such as will enable others skilled in the art to which it appertains to make and use the same.

This invention relates to vehicles and more particularly to removable wagon tops and has for an object to provide a wagon top which may be readily secured upon or removed from a wagon body, the top being constructed so that the sides and ends may be readily disconnected and swung downwardly upon their hinges for purposes of loading the wagon or airing the contents thereof.

Another object is to provide a wagon top of this character which may be readily secured upon the ordinary wagon body and which is so formed that the triangular ends and the downwardly slanting sides thereof will have their edges engaged in such manner and overlapped by flanges that are carried by said ends and sides as to form water tight joints and connections between the parts.

Another object is to generally improve the construction and increase the efficiency of removable wagon covers of this character.

With these and other objects in view, our invention will be more fully described, illustrated in the accompanying drawings, and then specifically pointed out in the claim which is attached to and forms a part of this application.

In the drawings: Figure 1 is a perspective view of a conventional form of wagon body with our removable top secured in position thereon. Fig. 2 is an end view of the cover or top removed. Fig. 3 is a vertical sectional view on the line 3—3 of Fig. 2. Fig. 4 is a vertical cross sectional view on the line 4—4 of Fig. 3. Fig. 5 is a transverse sectional view through the cover with the

sides swung to their downward position. Fig. 6 is a similar view through one end of the top or cover with the end section swung downwardly. Fig. 7 is a fragmentary horizontal section on the line 7—7 of Fig. 2. Fig. 8 is a fragmentary detail view of one corner of one of the slanting sides, showing the flanges carried thereby for engagement over the upper edge of the opposite side and outwardly of one of the ends for producing water tight connections between the parts.

Referring more specifically to the drawings, in which similar reference numerals designate corresponding parts throughout, 10 designates the wagon body which is of conventional form and upon which our improved removable cover is positioned.

Our improved cover consists of a frame 11 which is shown as being of rectangular form and of proper proportions to rest upon the wagon body 10. Secured to the inner and outer faces of the frame 11 are the spaced fingers 12 which extend to the upper edge of the frame and project below the lower edge of the frame, said fingers being secured vertically upon the sides and ends of the frame and the extended portions thereof being adapted for engagement against the inner and outer faces of the wagon body 10 to properly hold the cover in position and prevent the same from sliding off the wagon body.

Secured at the upper end of the fingers 12 are the hinges 13. The hinges 13 upon the fingers 12 at the ends of the frame 11 are also secured to the lower ends of the braces 14 carried upon the outer faces of the triangular end members 15, it being understood that the hinges are only secured to the fingers upon the outer face of the frame 11. It will also be understood that the braces 14 upon the ends 15 extend along the slanting sides of said end members 15 and vertically from the uppermost points of said end members to their lower edges. The lower edges of the end members 15 are beveled for proper engagement upon the correspondingly beveled upper edges of the ends of the frame 11 to allow the end members 15 to extend in a vertical direction when

properly positioned upon said ends of the frame and also to prevent the entrance of water between the end members 15 and the end of the frame 11. The hinges 13 upon 5 the upper ends of the fingers 12 carried by the sides of the frame 11 are secured to the slanting hinged side members 16, along the lower edges thereof. The upper edges of the sides of the frame 11 are beveled downwardly and upwardly while the fingers carried upon the outer face have their upper ends extended slightly above the upper edges of said sides and beveled downwardly and inwardly to permit of the lower edges of the 10 hinged slanting side members 16 being properly engaged upon the upper ends of said fingers and the upper edges of the sides to form a water tight joint or connection, when the slanting hinged side members are in their closed positions as will be later more 15 clearly understood.

The side members 16 may be formed of any suitable material and preferably include a frame 17 over which the cover 18 is secured which may be formed of metal, canvas or any other preferred material. The end pieces of each frame 17 are adapted for engagement against the downwardly extending sides of the triangular end member 15 20 and flanges 19 are secured along the outer edges of said ends for engagement outwardly of the end members 15 for the double purpose of retaining the end members in their vertical positions and for preventing the entrance of water at these points. 25

One of the hinged slanting side members 16 stops short at the top of the end members 15 while the other slanting hinged side member 16 is continued for a short distance to overlap the upper edge of the first side member 16, said second side member 16 carrying a flange 19' along its upper edge for engagement against the upper face of the first side member 16 along its upper 30 edge, thus forming a tight connection at this point and preventing the entrance of water or the like, as will be clearly understood by referring to the drawings. One of the slanting side members 16 carries the 35 hooks 20 upon its ends for engagement over the pins 21 carried by the opposite slanting side member 16 to connect said side members and retain the same tightly engaged against the slanting sides of the end members 15. 40 The short side member 16 has secured near its center a hasp 22 which is suitably bent to engage over the overlapping upper edge of the second side member 16, the free end of the hasp being adapted for engagement 45 over the staple 23 carried by the second side member 16 through which the lock or other means may be passed to prevent disengagement of the hasp and thus securely lock

the slanting side members 16 in closed position.

It will be clearly apparent that after removing the lock 24 and disengaging the hasp 22 from the staple 23 and disengaging the hooks 20 from the pins 21, the side members may be readily swung upon their hinges to their open positions, said sides extending from the upper edges of the sides of the frame. If desired, the end members 15 of the cover may then be swung to their open position. This is especially desirable for purposes of loading the wagon when the cover is positioned thereupon or for airing the contents of the wagon or unloading the same, as will be clearly apparent.

For purposes of strengthening the frame 80 11, the rods 25 may be passed through the extended sides of said frame, outwardly of the ends of said frame. If desired, a strengthening rod may be passed transversely through the frame for strengthening the frame at its central point and prevent spreading thereof. It will also be understood that if desired a suitable means may be employed for securing the frame 11 upon the wagon body 10 in such manner 85 that removal thereof by unauthorized parties will be impossible.

From the foregoing it will be evident that this form of removable wagon cover will be especially desirable for employment 95 on wagons used for hauling cotton, vegetables, live stock, etc., and when loading cotton in wagons during the cotton picking season, for the reason that the side members 16 and end members 15 may be readily 100 closed or opened as occasion may require.

It will of course be understood that minor changes in the details of construction may be made if desired without in the slightest degree departing from the spirit of our invention.

The vertical edges of the ends of the frame 11 are positioned between the spacing strips 11' carried vertically upon the sides of the frame adjacent the ends thereof and 110 the rods 25 are passed through the outer spacing strip, as clearly shown in Fig. 7. This specific construction of the frame 11, however, may be varied if desired.

What we claim is:—

The combination with a wagon body, of a rectangular frame having inner and outer spaced fingers secured upon the sides and ends thereof, said fingers having their lower ends extending below said frame for detachably engaging the body, end members hingedly connected to the outermost fingers of the frame ends, said members having beveled upper ends, side members having their lower edges hingedly connected to the outermost fingers carried by the sides of 115 120 125

the frame, one of said side members having a longitudinal strip carried by its free edge and adapted to engage the outer surface of the free edge of the other side member when said members engage the beveled upper edges of the end members, and means for locking the side members at their meeting edges.

In testimony whereof, we affix our signatures, in presence of two witnesses.

CHARLES H. BIGBIE.
FRANK G. TANNER.
